UNITED STATES PATENT OFFICE.

LEWIS L. HOLLADAY, OF LYNN, MASSACHUSETTS, ASSIGNOR TO GENERAL ELECTRIC COMPANY, A CORPORATION OF NEW YORK.

VENTILATING-FAN.

No. 850,226.

Specification of Letters Patent.

Patented April 16, 1907.

Application filed August 14, 1903. Serial No. 169,485.

To all whom it may concern:

Be it known that I, LEWIS L. HOLLADAY, a citizen of the United States, residing at Lynn, in the county of Essex, State of Massachusetts, have invented certain new and useful improvements in Ventilating-Fans, of which the following is a specification.

The present invention relates to rotary ventilating-fans, and more particularly to that class in which provision is made for automatically moving the device about a pivotal axis, so that the blast of air created by the fan will be caused to sweep over a considerable area instead of being confined to a particular channel.

The object of my invention is to provide improved means for automatically shifting the position of a screen from side to side of the pivotal axis of a rotary fan, whereby it is caused to oscillate back and forth by the action of the unbalanced thrust of its own air-blast upon the blast-impelling member thereof.

My invention contemplates the use, with a rotary ventilating-fan of any well-known construction and suitably supported upon a pivotal axis, of a screen adapted to diminish the volume of air delivered to the blast-impelling member at one side of the pivotal axis, stops suitably arranged for engaging the screen and retaining it momentarily in either of its operative positions, and means having a spring connection with the screen and actuated by a rotary part of the fan for putting the spring under tension and intermittently releasing the screen from the stops, so that it moves with a quick action to its opposite position.

For a better understanding of my invention reference may be had to the following description and the accompanying drawings, forming a part of this specification, in which —

Figure 1 is a side elevation of a rotary ventilating-fan pivotally supported and provided with means for automatically oscillating it embodying one form of my invention, and Fig. 2 is a right-hand elevation of the automatic oscillating means.

A is the frame of an electric motor, having its armature-shaft B projecting horizontally therefrom and carrying at its end the blast-impelling blades C, and D is the pivoted base upon which the motor-frame is supported.

These parts may be of any well-known construction and accordingly need not be described here in detail.

The screen is made from sheet material in the form of an eccentric plate or sector 1 and provided at its geometrical center with a hub 2, which is journaled upon the armature-shaft B between the blades C and the frame A. The diameter of the sector is shown somewhat greater than the diameter of the blast-impelling member C; but it is understood that in practice these relative dimensions will be changed according to the requirements of circumstances.

The means for momentarily holding the sector 1 in either operative position, as shown in Fig. 2, or the reverse consists of a lug 3, projecting from the edge of the sector, and two stops 4, arranged at diametrically opposite points in the path of the lug 3 and carried by a reciprocating rod 5, which is periodically raised or lowered sufficiently to move one of the stops 4 out of engagement with the lug 3 and bring the other into position to be engaged thereby upon the completion of a semirevolution of the sector. The rod 5 is provided with an elongated aperture 6 in a central enlargement, through which the armature-shaft B passes, and it is held in vertical position between a collar 7 and the end of the hub 2 on the shaft and a bracket 8, extending from the base D and provided at its end with a slot through which the rod passes, and a spring-clip 9, which operates to produce friction thereon to yieldably hold the rod in either of its extreme positions.

The means for giving the sector 1 a quick movement from one operative position to the other consists of a spiral spring 10, attached at one end to a pin 12, carried by the sector, and at the other end to a short shaft 13, which has a constant planetary movement about the armature-shaft, so that while the sector is held by one of the stops 4 the spring is tensioned, and then upon release of the sector the recoil of the spring operates to draw the sector into its opposite position, where it is engaged by the other stop 4. The means for moving the stops 4 out of the path of the lug 3 to release the sector consists of two inclines 14, carried by the rod 5, which are alternately brought into the circular path of the front end of the short shaft 13, so that the rod will be moved endwise thereby at the

completion of each semicircular movement of the shaft 13 about the axis of the armature.

The short shaft 13 is carried at the end of an arm 15, journaled upon the armature-shaft B, and is given a slow movement thereabout by a system of reducing-gears arranged as follows: A pinion 16 is fixed to the armature-shaft between the end of hub 2 and the arm 15 and meshes with a large gear 17, fixed 10 to the shaft 13 at the front of the arm 15. A second pinion 18 is fixed to the rear end of the shaft 13 and meshes with an idler-gear 19, which is journaled upon a stub-shaft 20, projecting from the side of the arm 15, and gear 15 19 meshes with and travels about a stationary gear 21, concentric with the armature-shaft and located between the arm 15 and the front end of the motor-frame A.

I do not intend to restrict myself to the 20 particular form or construction of parts shown and described herein, for it is apparent that they may be changed and modified without departing from my invention.

What I claim as new, and desire to secure 25 by Letters Patent of the United States, is—

1. The combination with a pivotally-supported ventilating-fan, of an eccentrically-pivoted screen supported in proximity to the blast-impelling member of the fan, means for 30 intermittently holding said screen in operative positions on opposite sides of the pivotal axis of the fan and releasing it therefrom, and means controlled by the revolution of the blast-impelling member on its axis for 35 automatically shifting said screen from one position to the other.

2. The combination with a pivotally-supported ventilating-fan, of an eccentrically-pivoted screen supported in proximity to the 40 blast-impelling member of the fan, means for intermittently holding said screen in operative positions on opposite sides of the pivotal axis of the fan and releasing it therefrom, and spring-controlled means for shifting said 45 screen from one position to the other.

3. The combination with a pivotally-sup-

ported ventilating-fan, of an eccentrically-pivoted screen pivotally supported in proximity to the blast-impelling member of the fan, means for intermittently holding said 50 screen in operative positions on opposite sides of the pivotal axis of the fan and releasing it therefrom, and spring-controlled means for shifting said screen from one position to the other.

4. The combination with a pivotally-supported ventilating-fan, of an eccentrically-pivoted screen pivotally supported in proximity to the blast-impelling member of the fan, stops for holding said fan in operative 60 positions on opposite sides of the pivotal axis of the fan, means for putting spring tension on said screen, and means for intermittently releasing the screen from said stops.

5. The combination with a pivotally-supported ventilating-fan, of an eccentrically-pivoted screen pivotally supported in proximity to the blast-impelling member of the fan, a continuously-revolvable part having 65 spring connection with said screen, means for holding the screen in either of its operative positions on opposite sides of the pivotal axis of the fan, and means for periodically releasing said screen from said holding means.

6. The combination with a pivotally-supported ventilating-fan, of an eccentrically-pivoted screen pivotally supported in proximity to the blast-impelling member of the fan, a reciprocating rod provided with stops adapted to engage a part of said screen and hold it in operative position with reference to the pivotal axis of the fan, and a continuously-revolvable part having spring connection with said screen and adapted to periodically engage and reciprocate said rod to release said screen therefrom.

In witness whereof I have hereunto set my hand this 12th day of August, 1903.

LEWIS L. HOLLADAY.
